UNITED STATES PATENT OFFICE.

ROLPH J. LACKNER, OF NEW YORK, N. Y., ASSIGNOR TO LACKNER PRODUCTS CORPORATION, OF BROOKLYN, NEW YORK, A CORPORATION OF DELAWARE.

SWINGING SCAFFOLD.

Application filed January 17, 1923. Serial No. 613,174.

To all whom it may concern:

Be it known that I, ROLPH J. LACKNER, a citizen of the United States, residing in the city of New York and State of New York, have invented certain new and useful Improvements in Swinging Scaffolds, of which the following is a specification.

The object of the present invention is to provide means whereby, if the suspending 10 rope at either end of a swinging scaffold should break at any point, the remaining strands of the rope will be automatically and positively clamped so that dropping of the scaffold will be prevented. The invention 15 seeks to provide means for the stated purpose which may be easily applied to any swinging scaffold and adjusted to the size of the same and to the number of strands or runs in the suspending rope. The invention 20 further seeks to provide means for the stated purpose which will be simple in the construction and arrangement of the several parts and which will not interfere in any way with the usual manipulation of the 25 scaffold. The invention is illustrated in the accompanying drawings and will be herein-after fully set forth.

In the drawings—

Figure 1 is a side elevation of a swinging scaffold equipped with my improvements, some of the parts being broken away;

Fig. 2 is an elevation of one end of the scaffold showing my improved safety device in the position assumed to prevent dropping 35 of the scaffold after the suspending rope breaks, and

Fig. 3 is a top plan view of the safety device with the suspending ropes in section.

The scaffold consists of a floor 1 carried 40 by rungs 2 between side rails 3 of the usual form. Hanger irons 4 are engaged around the end portions of the scaffold platform and are constructed at their upper ends with eyes 5 to be engaged by hooks 6 on the lower 45 pulley blocks 7, these hanger irons being also provided with eyes or loops 8 on their outer sides to receive the usual guard rail 9. The suspending rope 10 is trained back and forth between the pulley block 7 and the upper 50 pulley block 10' in the usual manner and the upper pulley block is equipped with a hook 11 engaged in a suspending bracket 12 which is anchored upon the roof in the usual manner.

In carrying out my invention, I secure to

the rope-anchoring structure 13, upon the upper end of the lower pulley block 7, a bracket or post 14 which rises above said anchoring structure and has a lever 15 pivotally attached to its upper end. Below the 60 pivot bolt 16 which connects the post 14 with the lever 15, a pivot bolt 17 is inserted through a suitable lug or ear on the said post and through the fork 18 extending outwardly from a clamping jaw 19 whereby to 65 pivotally connect said jaw to said post, it being understood that the rear end of the lever 15 is also forked, as shown at 20, so that the upper end of the supporting post or bracket 14 will be disposed between members of the lever and of the clamping jaw and lateral or twisting movement of the lever or the jaw relative to the said support will be prevented. At the outer side of the 70 supporting post 14, a link 21 is extended between the extremities of the fork 18 and the fork 20 so as to form a hinge connection between said members and relieve the strain upon the supporting post. The lever 15 extends outwardly to a point nearly or 75 quite in the vertical plane of the outermost rung 2 of the scaffold, and its outer extremity is bifurcated, as shown at 22, to receive the upper end of a connecting rod 23, the upper end of said rod being flattened, as 80 shown at 24, and provided with a longitudinally extending series of openings 25 therethrough whereby the attaching bolt 26 may be disposed at any desired point in the length of the connecting rod and vary the 85 effective length of said rod and the throw of the lever according to the demands of any particular scaffold and the weight imposed upon it. The lower end of the connecting rod 23 is constructed with an eye 27 90 to receive a pivot bolt 28, which bolt also passes through lugs 29 on the upper side of a clamping plate 30. The clamping plate 30 rests upon the floor 1 immediately over the end rung 2 and a bowed clamping plate 31 95 is disposed against the under side of the said rung and in engagement therewith and connected with the upper clamping plate 30 by bolts 32 inserted through the ends of the said plates at opposite sides of the rung, as clearly 100 shown in Fig. 1, thereby securely anchoring the connecting rod to the end of the scaffold. Pivotally attached to the lever 15 and arranged to co-operate with the jaw 19 is a 105 second jaw 33 which is arranged at the op- 110

posite side of the suspending rope 10 from the jaw 19. The jaw 33 is formed on the inner end of an arm 34 which is disposed below the lever 15 and is provided intermediate its ends with upstanding lugs 35 disposed at opposite sides of the lever 15 and pivotally attached thereto, as will be readily understood. In the outer end of the arm 34 is mounted a set bolt 36 which bears 5 against the under edge of the lever 15 and which may be adjusted in an obvious manner to swing the arm 34 about its pivotal connection with the lever so that the jaw 33 will be set closer to or farther from the suspending rope. The jaws 19 and 33 extend laterally in both directions to a sufficient extent to receive between them all the runs or strands of the suspending rope, as will be readily understood on reference to Fig. 3, 10 and the central portions of the jaws are bowed, as indicated at 37 and 38, to prevent possible contact with the rope-anchoring structure 13 on the lower pulley block when the device is operated. It will, of course, be understood that one outer run or strand of the suspending rope is carried downwardly below the lower pulley block and is tied about the hook 6 and eye 5 so as to hold the rope against slipping and thereby maintain 15 the scaffold at the desired point. To accommodate the outer runs of the cable when the scaffold is being adjusted, I provide removable closures or keepers which are adapted to bridge the ends of the clamping jaws 19 and 33 so that all the runs of the rope will be confined between the jaws. These keepers 39 consist of small plates having flanges or lips 40 at one end disposed at a right angle to their main portions and, near the 20 said flanges, the keepers are constructed with openings through which securing bolts 41 may be inserted to engage sockets provided therefor in the ends of the jaw 33, the flanges 40 fitting against the outer side of said jaw, as shown clearly in Fig. 3. When the rope is being trained about the pulleys, these keepers may be removed so that the runs or strands of the rope may be easily brought into position between the jaws. 25 After the rope has been satisfactorily trained about the pulleys, the keepers are brought into position and secured and will then restrain the several runs of the cables so that they cannot pass beyond the ends of the jaws and assume a position in which they cannot be engaged by the jaws. In the normal position of the parts, the free ends of the keepers will bear lightly against the outer end surfaces of the jaw 19 so that, 30 while they will completely bridge the space between the jaws, they will not interfere with the relative movement of the same in any way.

The scaffold is employed and adjusted from point to point as the work being per-

formed demands in the usual manner of any ordinary swinging scaffold. Normally, the jaws 19 and 33 are out of contact with all the strands of the suspending rope but are disposed close enough to said strands to quickly engage them if the occasion should arise, although leaving sufficient play to permit the strands to move readily and easily in adjusting the scaffold. Should the rope break at any point, the end of the scaffold supported by the broken rope obviously at once starts to fall and the scaffold assumes the inclined position shown in Fig. 2. When the end of the scaffold drops, as just stated, the connecting rod 23 follows the movement and inasmuch as the movement at the extreme end of the scaffold is greater than the movement at points spaced inwardly from the end, the descent of the connecting rod will be relatively greater and more rapid than the descent of the pulley block 7 with the post 14 carried thereby. As a result, the lever 15 is swung about its pivotal connection with the supporting post 14, as shown in Fig. 2, and the clamping jaw 33 is forced against the rope. The movement of the lever is transmitted through the link 21 to the jaw 19 so that said jaw is swung about its pivot 17 and is thereby caused to grip the rope. The jaws 19 and 33 are in this manner instantly carried against the opposite sides of all the strands or runs of the rope and effectually and positively grip the same, as shown in Fig. 2, so that they constitute a very strong brake and at once arrest the movement of the rope so that the fall of the scaffold will be arrested and injury to the workmen or possible loss of life will be avoided.

It will be readily noted from the foregoing description, taken in connection with the accompanying drawings, that I have provided a very simple and inexpensive apparatus which may be readily applied to any swinging scaffold and which will operate instantly and automatically upon the breaking of the rope to clamp the rope and prevent dropping of the scaffold.

Having thus described the invention, what is claimed as new is:

1. A safety device for swinging scaffolds comprising a pair of jaws disposed at opposite sides of the scaffold-suspending rope and normally free thereof, a lever carrying said jaws, means for supporting said lever from a pulley block of the scaffold, and a connection between the end of the lever and the end of the scaffold whereby dropping of the end of the scaffold will cause the jaws to grip the suspending rope.
2. A safety device for swinging scaffolds comprising a lever, means for supporting the lever upon a relatively fixed part of the scaffold, a pair of clamping jaws pivotally suspended on said lever and disposed

at opposite sides of the scaffold-suspending rope, a connecting rod adjustably pivoted to the outer end of the lever, an anchoring device to be secured to the end of the scaffold, and a pivotal connection between said anchoring device and the lower end of the connecting rod.

3. A safety device for swinging scaffolds comprising a supporting post to be secured to a relatively fixed part of the scaffold, a lever pivotally mounted upon the upper end of said post and spanning a run of the scaffold-suspending rope and extending outwardly toward the end of the scaffold, a clamping jaw pivotally mounted upon said supporting post below the lever at one side of the runs of the scaffold-suspending rope, a link connecting the inner end of said jaw with the inner end of the lever, a co-operating jaw pivotally suspended upon the lever at the opposite side of the runs of the scaffold-suspending rope, adjustable means for maintaining the latter jaw in fixed relation to the lever, and a connecting rod pivoted to the outer end of the lever and adapted to be pivoted to the end of the scaffold.

4. A safety device for swinging scaffolds comprising a supporting post to be secured to a relatively fixed part of the scaffold, a lever mounted upon said post, a clamping jaw pivoted upon said post below the lever, a connection between the lever and the said jaw, a co-operating jaw disposed at the opposite side of the runs of the scaffold-suspending rope, a lug rising from said second jaw and pivoted to the lever, a set bolt mounted in the outer end of the said jaw and bearing against the under edge of the lever, and a connecting rod pivoted to the outer end of the lever and constructed to be pivoted to the end of the scaffold.

5. A safety device for swinging scaffolds

comprising a supporting member to be secured to a relatively fixed part of the scaffold, a lever mounted upon the upper end of the said member, a rope-clamping jaw mounted upon said member below the lever, a connection between the lever and said jaw, a second rope-clamping jaw pivotally suspended upon the lever, a rod pivoted to the outer end of the lever and adapted at its lower end to be pivoted to the end of the scaffold, and removable keepers bridging the ends of the said clamping jaws.

6. A safety device for swinging scaffolds comprising a lever, means for supporting the lever from a relatively fixed member of the scaffold, a jaw disposed below the lever, a connection between said jaw and the lever, a second co-operating jaw pivotally suspended from the lever, and keepers bridging the ends of the said jaws and secured to the second-mentioned jaw, said keepers being provided with flanges bearing against the outer surface of the second-mentioned jaw and having their free ends arranged in juxtaposition to and movable past the ends of the co-operating jaw.

7. A safety device for swinging scaffolds comprising a pair of opposed cooperating jaws spanning all runs of the scaffold-suspending cable and normally out of engagement with the cable, a lever fulcrumed upon a relatively fixed part of the scaffold and connected with the jaws to move them in opposite directions, and a connecting rod attached at its upper end to the lever and at its lower end to the scaffold whereby upon dropping of the scaffold the jaws will be caused to grip the several runs of the suspending cable.

In testimony whereof I affix my signature.

ROLPH J. LACKNER. [L. S.]
